Patented Dec. 1, 1914.

UNITED STATES PATENT OFFICE.

PERCY P. HOPP, OF NEW YORK, N. Y.

AWNING.

1,119,161.

Specification of Letters Patent.

Patented Dec. 1, 1914.

Application filed April 18, 1914. Serial No. 832,673.

To all whom it may concern:

Be it known that I, PERCY P. Hopp, a citizen of the United States of America, residing at New York, in the county of Bronx 5 and State of New York, have invented certain new and useful Improvements in Awnings, of which the following is a specification.

The present invention relates to awnings 10 and has for its object to improve the construction of the awning as to enable of its being easily folded up and covered during the season when it is not in use. The new awning need not be taken off, but can be left 15 on all the time so that its durability is greatly increased.

With this and other objects in view, my invention consists in the construction, arrangement and combination of parts as are 20 fully set forth in the description and annexed claims.

In the accompanying drawing which forms part of this specification and in which similar reference characters denote corresponding parts, Figure 1 is a perspective view of my improved awning; Fig. 2 a cross section on line 2—2 of Fig. 1; Fig. 3 a vertical section of the folded and covered awning; Fig. 4 an enlarged side view of a part 30 of the awning; Fig. 5 a detail view of the cover and Fig. 6 a front view of a modified form of construction.

Specifically referring to the drawing, *a* denotes the awning which is formed with lateral triangular wings or flaps *a'* that extend from the bottom to about the middle 35 part and not as hitherto to the top of the awning.

The support of the awning may be the 40 same as that described and shown in my former United States Patent No. 989,709, issued April 18, 1911, or may be of any other suitable construction. At each side of the awning there is the ordinary vertical guide 45 rod *b*, along which the awning is guided during its up and down movement. For folding and unfolding the awning there are the ordinary pulleys *c* and adjusting cords *d*. At the bottom the front part of the 50 awning material is fastened to a U-shaped bar *e*, which at its ends carries sockets *f* that slidably are mounted on the vertical guide rods *b*. The wings or flaps *a'* are free and are each provided with a spring hook *g* of 55 any suitable construction, which are fas-

tened to the back of the material by rings *g'* or the like. Suitably fastened to each socket is a ring *h* with which the corresponding hook *g* of the lateral flap *a'* is adapted to be engaged, when the awning is 60 down. When the awning is raised, the flaps are detached from the rings *h* and may be folded against the back of the front part of the awning and shoved between the adjusting cords *d* and the awning material. At 65 the points *a''* where the flaps terminate there is an additional spring hook *i* at each side of the awning fixed to the latter in the same manner as the bottom hooks *g* and adapted to be engaged with rings *j* loosely mounted 70 in the vertical guide rods *b*. By these additional hooks and rings the upper part of the awning will be held flat in a downwardly directed position instead of projecting obliquely or roof like as the lower part does, 75 and will thus act as a window shade. There being no lateral flaps at the upper part of the awning a free ventilation of air through the sides will be afforded. The ventilation may be increased by unhooking the sides 80 from the rings *j*. Instead of the hooks *g* and rings *j* a rod or bar *k* (Fig. 6) may be fastened across the middle part of the awning which at its ends carries sockets *l* slidably engaging the vertical guide bars *b*. 85

A covering *m* of waterproof material may be used for covering the awning when the latter is raised and folded up (Fig. 3). The covering *m* (Fig. 5) is cut out as at *m'* to allow of its being passed around the 90 supports *n*, and may be provided with suitable means, as press buttons *m''* and eyelets *m'''* or the like, to allow of the fastening of the cover around the folded awning. By making the wings or flaps detachable, the 95 awning can be folded up into a narrow roll which will not obstruct the light at the upper end of the window and which allows of the use of the cover to protect the awning against the weather during the season it is 100 not in use.

What I claim and desire to secure by Letters Patent is:

1. The combination with stationary lateral guide members, of an awning, a rigid 105 member extending crosswise through and attached to the middle portion of said awning and having sockets slidably engaging the said guide members.

2. The combination with stationary lat-

eral guide members, of an awning having lateral flaps extending from the bottom to about the middle part of said awning, a rigid member extending crosswise through 5 and attached to the middle part of said awning and having sockets slidably engaging the said guide members.

In testimony whereof I affix my signature in presence of two witnesses.

PERCY P. HOPP.

Witnesses:

**WILLIAM SEITZ,
ARNO C. POSTLER.**
